UNITED STATES PATENT OFFICE.

CLAYTON T. EAID, OF PORTLAND, OREGON.

SAFETY-BUNK FOR LOGGING-CARS.

1,071,609.

Specification of Letters Patent. Patented Aug. 26, 1913.

Application filed May 2, 1913. Serial No. 765,011.

To all whom it may concern:

Be it known that I, CLAYTON T. EAID, a citizen of the United States, residing at Portland, in the county of Multnomah and State of Oregon, have invented certain new and useful Improvements in Safety-Bunks for Logging-Cars, of which the following is a specification.

My invention relates to bunks to be applied to logging-cars and may be considered as a further amplification and development of my patents numbered 1,050,929, issued January 21st, 1913, and 1,055,150, issued March 4th of the same year.

The primary object of my present invention is to provide a device of this kind that is of simpler construction than my previous inventions, yet efficient in action, durable, inexpensive in first cost by reason of its lack of intricate mechanisms and economy of time in assemblage.

Other objects and advantages of my invention will be made clearly apparent in the following specification, taken in connection with the accompanying drawings forming part of this application, in which:—

Figure 1 is a top plan view of my invention; Fig. 2 is a side elevation of same; Fig. 3 is a bottom plan view of same; Fig. 4 is an end elevation of Fig. 2; Fig. 5 is a perspective of the rack-bar with the operating lever attached thereto; Fig. 6 is a side elevation of one of the rolls to which the toe of the stake fastens when said stake is locked; Fig. 7 is a vertical section through line A A of Fig. 1; Fig. 8 is an enlarged longitudinal section through Fig. 1, showing the stake fastened and holding a log, and the position of the lever which operates the rack-bar when said stake is locked; Fig. 9 is a similar view showing the stake released, and Fig. 10 is an enlarged side elevation of one of the cranks to which are pivoted the levers which operate the rack-bars.

In the practice of my invention I employ beams 2, which are spaced apart by channel-iron 3 adjacent the upper edges of said beams, braces 4, consisting of a bottom-plate and two perpendicular sides integral with said bottom plate; said braces being at-

tached adjacent the ends and bottom portions of said beams, and brace 5 of similar construction to braces 4 attached to the beams intermediate said braces 4; said beams, channel-iron, and braces being fastened together by means of rivets 6.

Secured to the inside of plates 2 and passing longitudinally thereof at convenient lengths are angle-irons 7 placed parallel to channel-iron 3 at such vertical distance therefrom as to conform with the diameter of pins 8 which are integral with stakes 9 for purposes hereinafter shown and explained.

Passing from the ends of channel-iron 3 to convenient distances are central longitudinal slots 10 equal in lateral dimensions to the thickness of stakes 9 which fit into said slots, thus preventing said stakes from lateral motion; the vertical and longitudinal motion being governed by pins 8 sliding between beams 2, channel-iron 3 and angle-irons 7.

Slidably mounted intermediate beams 2 and resting on braces 4 and 5 respectively are rack-bars 11 with teeth 12 integral therewith, and perforated lugs 13 forming one end thereof; the perforations 14 being engaged by trunnions 15 of levers 16 which are pivotally attached to one of the arms of cranks 17; the opposite arms of said cranks being pivoted to and passing through one of the walls of beams 2 and braces 4 respectively; each of said cranks being attached at diagonally opposite points with relation to the other.

Placed superjacent the rack-bars and revolvably mounted horizontally intermediate beams 2, are rolls 18 which engage toes 20 of stakes 9 when said stakes are in the position shown in Fig. 8; said toes are held in such position by the pressure of teeth 12 against them; the tendency of the pressure of the logs against the upper portions of stakes 9 being to hold toes 20 against teeth 12 of rack-bars 11 and said rolls 18. It will be noted that in Fig. 8 the centers of the arms of cranks 17 and lugs 13 of rack-bars 11 are in longitudinal alinement; when said centers are in this relation to each other, one of the teeth of the rack-bar presses

against toe 20 of stake 9 and locks said stake in position to prevent the logs from rolling off the bunk. When the rack-bar is unlocked as shown in Fig. 9 the centers of 5 the arms of cranks 17 are in vertical alinement with each other and the edges of teeth 12 of rack-bar 11 are in perpendicular alinement with points on the periphery of rolls 18; it will be noted that the width of teeth 10 12 is equal in dimensions with the diameter of said rolls, thus making the space between the teeth the same width as the space intermediate the rolls in order to allow the pressure of the logs to trip the stakes when the 15 toes are disengaged from the rolls when the rack-bar is released by manual operation of lever 16.

In order to operate my invention the complete device must be attached either to 20 trucks or platform cars. If attached to trucks the bunks must be fastened by king-bolts passing through apertures 21, and if applied to platform cars said bunks are attached by means of U-shaped bolts passing 25 through apertures 22. When the bunks are so attached the stakes are locked in the position shown in Fig. 8 and the logs piled thereon to any height consistent with safety and convenience. The logs are usually piled 30 in such order that the second tier rests between the spaces formed by the logs of the lower tier and each tier diminishing by one log until but a single space is left and one log placed therein which completes the pile. 35 To release the stakes and allow the logs to unload it is necessary for the operator to release stakes 9 by lifting levers 16 from the position shown in Fig. 8 to the position indicated in Fig. 9 which brings the toes of 40 said stakes in vertical alinement with the space between two of rolls 18; when forced into said position by the pressure of the logs against stakes 9, said stakes fall downward to the position indicated in Fig. 9, thus 45 allowing the logs to roll off the bunks instantly.

It is obvious from the construction of my invention that stakes 9 can be placed in several longitudinal positions; said positions 50 being predetermined by the number of teeth in the rack-bars and the number of rolls superjacent said rack-bars. These various positions will prove of great convenience in adjusting the stakes to engage the first tier 55 of logs. My improved bunks are so constructed that the stakes can only be released by manual operation and cannot disengage accidentally as will be discerned by a close observation of the operating mechanisms in 60 Fig. 8. In said figure it will be seen that the greater the pressure on the stakes, the firmer toes 20 of said stakes press against the rolls which engage said toes, hence the greater the pressure on the stakes,

greater the tendency of said stakes to remain 65 locked. Another salient feature of my invention is that it serves as a safety appliance for workmen who operate such devices, as well as being a mechanism of great utility; the feature of safety residing in the 70 fact that the stakes can only be released at the opposite side of the car from where the workman stands, thus preventing the logs from rolling on the operator and causing 75 him injury.

My improved bunk may be constructed of any material and made of any size deemed suitable for such a device, and while I have described and illustrated a preferred form 80 of construction and combination of elements considered essential in materializing my invention, I desire to include in this application all mechanical equivalents and substitutes that may be fairly considered to lie 85 within the scope and purview of my invention as defined in the appended claims.

Having thus fully described my invention, so that others skilled in the art to which it appertains may be enabled to construct and use the same, what I claim and desire to secure by Letters Patent, is:

1. In a device of the character described, the combination of beams spaced apart by means of a channel-iron and braces, angle-irons attached to said beams parallel with 95 the channel-iron, central longitudinal slots adjacent the ends of said channel-iron, stakes passing through said slots, pins attached to said stakes, said pins passing between the spaces formed intermediate said 100 channel-iron and angle-irons, rack-bars slidably mounted intermediate the lower portions of the beams and resting on the braces, rolls revolvably attached to the beams superjacent the rack-bars, said rolls 105 being adapted to engage the toes of the stakes, and means to lock and release said stakes, substantially as described.

2. In a device of the character described, the combination of beams spaced apart by 110 means of a channel-iron riveted to said beams intermediate their upper edges and braces passing beneath and overlapping the outside portions of said beams, angle-irons attached to said beams parallel with said 115 channel-iron, central longitudinal slots adjacent the ends of said channel-iron, stakes passing through said slots, pins attached to said stakes, said pins passing between the spaces formed intermediate said channel-iron and angle-irons, rack-bars slidably mounted intermediate the lower portions of the beams and resting on the braces, rolls 120 revolvably attached to the beams superjacent the rack-bars, said rolls being adapted 125 to engage the toes of the stakes, and means to lock and release said stakes, substantially as described.

3. In a device of the character described, the combination of beams spaced apart by means of a channel iron riveted to said beams intermediate their upper edges and 5 braces passing beneath and overlapping the outside portions of said beams, angle-irons attached to said beams parallel with said channel-iron, central longitudinal slots adjacent the ends of said channel-iron, stakes passing through said slots, pins attached to said stakes, said pins passing between the spaces formed intermediate said channel-iron and angle-irons for the purpose of guiding the longitudinal motion of said stakes, 10 rack-bars slidably mounted intermediate the lower portions of the beams and resting on the braces, rolls revolvably attached to the beams superjacent the rack-bars, said rolls being adapted to engage the toes of the stakes, and means to lock and release said stakes, substantially as described. 15
4. In a device of the character described, the combination of beams spaced apart by means of a channel-iron riveted to said beams intermediate their upper edges and 20 braces passing beneath and overlapping the outside portions of said beams, angle-irons attached to said beams parallel with said channel-iron, central longitudinal slots adjacent the ends of said channel-iron, stakes adapted to engage with logs passing through said slots, pins attached to said stakes, said pins passing between the spaces formed intermediate said channel-iron and angle-irons for the purpose of guiding the longitudinal motion of said stakes, rack-bars slidably mounted intermediate the lower 25 portions of the beams and resting on the braces, a plurality of rolls revolvably attached to the beams superjacent the rack-bars, said rolls being adapted to engage the toes of said stakes and being equal in number to the teeth of the rack-bars in order 30 that the stakes may be longitudinally adjusted to the width of one tier of logs, said rolls being adapted to engage the toes of said stakes when said stakes are locked, cranks pivoted to the beams at diagonally opposite points, levers pivoted to said cranks and said rack-bars, said levers serving to lock and release said stakes when 35 said levers are actuated by manual effort, substantially as described. 40
5. In a device of the character described, the combination of beams spaced apart by means of a channel-iron riveted to said beams intermediate their upper edges and 45 braces passing beneath and overlapping the outside portions of said beams, angle-irons attached to said beams parallel with said channel-iron, central longitudinal slots adjacent the ends of said channel-iron, stakes adapted to engage with logs passing through said slots, pins attached to said stakes, said pins passing between the spaces formed by the channel-iron and angle-irons for the purpose of guiding the longitudinal motion of 50 said stakes, rack-bars slidably mounted intermediate the lower portions of the beams and resting on the braces, a plurality of rolls revolvably attached to the beams superjacent the rack-bars, said rolls being adapted to engage the toes of said stakes when such stakes are locked, cranks pivoted to each of the beams at diagonally opposite points, 55
- braces, rolls revolvably attached superjacent the rack-bars, said rolls being adapted to engage the toes of said stakes when such stakes are locked, cranks pivoted to the beams at diagonally opposite points, levers pivoted to said cranks and said rack-bars, 60 said levers serving to lock and release said stakes when said levers are actuated by manual effort, substantially as described. 65
6. In a device of the character described, the combination of beams spaced apart by means of a channel-iron riveted to said beams intermediate their upper edges and 70 braces passing beneath and overlapping the outside portions of said beams, angle-irons attached to said beams parallel with said channel-iron, central longitudinal slots adjacent the ends of said channel-iron, stakes adapted to engage with logs passing through said slots, pins attached to said stakes, said pins passing between the spaces formed 75 intermediate said channel-iron and angle-irons for the purpose of guiding the longitudinal motion of said stakes, rack-bars slidably mounted intermediate the lower portions of the beams and resting on the 80 braces, a plurality of rolls revolvably attached to the beams superjacent the rack-bars, said rolls being adapted to engage the toes of said stakes and being equal in number to the teeth of the rack-bars in order 85 that the stakes may be longitudinally adjusted to the width of one tier of logs, said rolls being adapted to engage the toes of said stakes when said stakes are locked, cranks pivoted to the beams at diagonally opposite points, levers pivoted to said cranks and said rack-bars, said levers serving to lock and release said stakes when 90 said levers are actuated by manual effort, 95 substantially as described. 100
7. In a device of the character described, the combination of beams spaced apart by means of a channel-iron riveted to said beams intermediate their upper edges and 105 braces passing beneath and overlapping the outside portions of said beams, angle-irons attached to said beams parallel with said channel-iron forming runways for stakes, central longitudinal slots adjacent the ends of said channel-iron, stakes adapted to engage with logs passing through said slots, pins forming part of said stakes, said pins passing between the spaces formed by the channel-iron and angle-irons for the purpose of guiding the longitudinal motion of 110 said stakes, rack-bars slidably mounted intermediate the lower portions of the beams and resting on the braces, a plurality of rolls revolvably attached to the beams superjacent the rack-bars, said rolls being adapted to engage the toes of said stakes when such stakes are locked, cranks pivoted to each of the beams at diagonally opposite points, 115
- 120
- 125

levers pivoted to said cranks and said rack-bars, each of said levers being arranged to operate the stake at the end of the bunk remote therefrom when said lever is actuated by manual effort, substantially as described.

In testimony that I claim the foregoing

as my own, I hereunto affix my signature in the presence of two subscribing witnesses.

CLAYTON T. EAID.
